UNITED STATES PATENT OFFICE.

DERRICK N. LEHMER, OF CHICAGO, ILLINOIS.

PERMUTATION-PADLOCK.

SPECIFICATION forming part of Letters Patent No. 650,404, dated May 29, 1900.

Application filed January 9, 1899. Serial No. 701,627. (No model.)

To all whom it may concern:

Be it known that I, DERRICK N. LEHMER, a citizen of the United States, residing in the city of Chicago, county of Cook, and State of Illinois, have invented certain new and useful Improvements in Permutation - Locks; and I do hereby declare the following to be a full, clear, and exact description of the invention, such as will enable persons who are skilled in the art to which it appertains to make and use the same.

My invention has reference to improvements in permutation-locks, and more especially to padlocks of this class.

The objects of my invention are to improve generally the construction of permutation-padlocks by simplifying and reducing the cost and number of parts usually required in this class of locks and by numbering and indexing the dial so that the characters thereon will constitute a system of mnemonics for assisting the memory to retain the combination for which the lock may be set and to increase the permissible number of permutations usual in such locks.

With these and other objects in view my invention consists in the novel construction, combination, and relation of parts hereinafter more fully described, and particularly pointed out in the appended claims and illustrated in the accompanying drawings, which form a part hereof, in which—

Figure 1 is a perspective view of my completed lock. Fig. 2 is a side view with one of the side covers, dial, and tumbler-wheels removed, showing the lock closed. Fig. 3 is a similar view showing the lock open. Fig. 4 is a side view of the case of the lock with everything removed except one tumbler - wheel. Fig. 5 is a vertical cross-section through line 5 of Fig. 2. Fig. 6 is a partially-perspective edge view of the lock when closed.

Like letters of reference refer to similar parts in all of the views.

The containing-case is composed of the ring *a* and the two side covers *b b'*. One of the covers may be made integral with the ring, as shown in Figs. 5 and 6. Both of the covers are perforated through their centers, in which studs *b²* and *b³*, respectively, have bearings. The covers are preferably countersunk on the outside surface, into which dial-

disks *b⁴* and *b⁵* are placed, so that their outside surfaces come practically flush with the outside rim of the respective covers. The 55 dials *b⁴* and *b⁵* are each connected to a tumbler-wheel *c* and *c'* by the studs *b²* and *b³*. The studs are each rigidly attached to their respective dials; but they are attached to their respective tumbler-wheels by means of soft 60 solder or the like. The reason for this especial means of attachment will be hereinafter more fully explained. The bow *d* swings on the pivot *d'* and has an extension *d''*, which projects into the case and moves between the 65 two tumbler-wheels *c* and *c'*. A spring *e* is attached to the case-ring *a*, one end of which impinges against the extension *d''* with sufficient pressure to open or throw back the bow *d* when released by the dog *f*. The other end 70 of the spring *e* bears against the dog *f*, so as to hold it normally in the position shown in Fig. 2.

The spring-tumbler *g* (shown in Figs. 2 and 3) is attached to the inside of the case-ring 75 and normally bears against its inner surface and presses the button *h* outward in position. (Shown in Figs. 1 and 2.) The tumbler *g* is bent practically at right angles at its upper end, and it is adapted to enter notch *c²* of 80 wheels *c* and *c'*. Small notches *c³* are cut into the face-surface of the tumbler-wheels *c* and *c'*.

The dial *b⁴* is preferably numbered to correspond with the face of a clock. For a convenient means for turning the dial I prefer to engine-turn or to cross-cut the center part of the dial, as shown at *b⁶*, Fig. 1, so that when the pressure of the finger or thumb is applied against this portion of the dial there 90 will be sufficient friction to turn the dial and the attached tumbler-wheel.

Taking a vertical line through the center of Fig. 5, the lock on one side of the line is an exact duplicate of that on the other side. Fig. 95 2 shows the lock closed; but the combination is in position to open it by the mere pressure of the button *h*.

The operation of my lock is as follows: Suppose the lock combination is set to open at 100 12.30, you should remember that when looking at the lock, as shown in Fig. 1, the dial at which you are looking represents the hour, and the dial on the obverse side, which is an

exact duplicate of the former dial, represents minutes, or the respective dials may be marked "hours" and "minutes." Then you set the "XII" on the point I, as shown in Fig. 5 1, turning the dial by a slight pressure of the finger, as explained. Then the notch c^2 will come opposite the upper end of the tumbler g , as shown in Fig. 2. After this has been done set the "VI" of the dial-index on the 10 opposite side to point I. This will complete the combination of "12" on the hour side and "30" on the minute side. Then the notches c^2 of the tumbler-wheels will both be in position shown in Fig. 2, so that when the button 15 h is pressed inward the tumbler g will enter the notches c^2 of tumbler-wheels c and c' . The end of the tumbler g will then press against the dog f , displacing it against the resistance of spring e , liberating the bow d , and unlocking 20 the lock. The other end of spring e causes the bow d to fly open, as shown in Fig. 3. To close the lock, all that is necessary is to depress the bow d until the notch thereon passes the notch on the dog f , when the spring 25 e will force the dog f into the notch on the bow d and hold it locked. Now if the tumbler-wheels are moved so that the deep notches c^2 thereon are not in a coincident position, as shown in Fig. 3, then the button h cannot be 30 sufficiently depressed to displace the dog f , because it will be arrested by the tumbler-wheels c c' , as will be plainly evident.

The object of the small notches c^3 is to prevent the deep notches c^2 from being found by 35 gently depressing the button and turning the dials, which might be easily accomplished if the surfaces of the tumbler-wheels were smooth instead of being notched, as shown.

To change the combination all that is necessary to do is to place the tumbler-wheels in 40 positions shown in Fig. 3, depress the button h , so as to hold them in position, and turn the lock on its side, with the dial to be changed face up. It will be noticed that the studs b^2 and b^3 45 extend from their respective dials into counterbored holes made in the tumbler-wheels. These counterbored holes are filled with soft solder for securing the studs to the wheels. Then hold a hot soldering-iron on the center 50 of the dial until the solder uniting the dial

and stud b^2 or b^3 has melted. Then turn the dial to the desired new position and allow the solder to cool and reunite the dial and respective tumbler-wheel together by means of the stud. In this way both or either dial may be 55 changed as often as desired. When the lock is turned in the horizontal position described, the solder will be retained in the counterbored cups formed in the tumbler-wheels when melting and will not adhere to the covers. 60

I have found from experience that it is much easier to remember a combination when the figures correspond to some hour of the day than it is to remember arbitrary numbers.

I desire it understood that I do not limit myself to the specific details of construction herein shown and described, but reserve to myself the right to make such changes in the form and arrangement of the various parts of the apparatus as fairly fall within the spirit 65 and scope of my invention.

Having thus fully described my invention, what I claim as new and useful, and desire to secure by Letters Patent, is—

1. In a permutation-lock the combination 75 of a dial, or indicator, mounted on the outside case thereof; a tumbler-wheel within the said case, a stud for connecting the said dial and tumbler-wheel together and a soldered joint between the said stud and tumbler-wheel, 80 substantially as shown and described.

2. In a permutation-lock the combination 85 of a containing-case; a dial on each side of the case having a clock-face index, said dials being connected to tumbler-wheels within the containing-case; a dog pivoted to operate between the said tumbler-wheels adapted to normally engage with the bolt or bow of the said lock; a tumbler for displacing the said dog, and a push-button for depressing the said 90 tumbler, substantially as shown and described.

In testimony whereof I have signed this specification, in the presence of two subscribing witnesses, this 5th day of January, 1899. 95

DERRICK N. LEHMER.
